UNITED STATES PATENT OFFICE

OTTO E. RUHOFF AND EDGAR J. McEACHRON, OF WAUSAU, WISCONSIN

DRY BATTERY

Application filed April 14, 1926. Serial No. 101,945.

This invention relates particularly to an improved method of constructing dry-batteries of the upright type adapted for radio purposes, the dry-cells being horizontally disposed in the battery-assembly.

The primary object is to provide a method of producing a staunch and durable battery which can be manufactured at moderate cost. The invention is illustrated in its preferred embodiment in the accompanying drawings, in which—

Fig. 1 represents a perspective view of an inner pasteboard box fitted with a cellular structure dividing the box into cell-compartments, this view showing some of the compartments containing cells; Fig. 2, a broken perspective view illustrating the manner in which the inner assembly slips into an outer pasteboard container, or casing; Fig. 3, a broken perspective view showing the top portion of the battery; Fig. 4, a broken transverse vertical sectional view taken as indicated at line 4 of Fig. 3; Fig. 5, a similar view taken as indicated at line 5 of Fig. 3; and Fig. 25 6, a view similar to Fig. 5, but showing a slight modification.

In the construction illustrated in Figs. 1-5 inclusive, A designates an inner pasteboard box which is open at one of its broad sides and which is fitted with an egg-crate pasteboard structure A' which divides the box into compartments; B, a series of dry-cells within the compartments mentioned which have their carbon poles presented to the open side 30 of the box; and C, an outer container, or casing, for receiving the inner battery-assembly, said casing being open at one end and provided with a closure C' for the open end.

The cells may be assembled in the compartments of the inner pasteboard box while the latter is resting upon the broad side 1 which at this time forms the bottom of the box. After the assembly of the cells within the inner box, the latter is slipped endwise through the open end of the outer container C, and the closure C' is then applied. When the container is in the upright position in which it is intended to be used, the cells are horizontally disposed, and the closure C' constitutes the top of the battery.

It is preferred to apply to the inner surface of the bottom 1 of the box A a thick coating of melted asphaltum, or pitch, 2, and to then insert the egg-crate structure A' into the box. The egg-crate structure is pressed down into the box so that the lower edges of the pasteboard strips which form the structure become imbedded in the seal 2, thus making liquid-tight joints. The egg-crate structure may itself be impregnated with paraffin, or the like, if desired.

The dry-cells B commonly (but not necessarily) are of the flashlight type, employing a zinc-cup container 3 as the negative pole and a central carbon 4 as the positive pole. 65 Carbon poles are equipped with brass caps 4'. The cells may be connected in series, or otherwise, by means of wires 5.

At one end of the series, the carbon pole of the cell is provided with a terminal 6 which may be connected in the manner shown in Fig. 4. At the other end of the series, the zinc cup has connected therewith a terminal 7 which may be applied in the manner shown in Fig. 5. At an intermediate point, a terminal 8 may be connected with a zinc cup of the cell.

In making the assembly, the dry-cells are introduced into the box A in the manner illustrated in Fig. 1. In the figure just referred to, one end wall 9 of the box is shown removed. This wall is provided with perforations 10 through which the terminals 6, 7 and 8 may extend. It will be understood that the terminals just mentioned are attached to cells of the topmost row.

The end wall 9 of the box A may be severed from the box to enable the terminal rods to be passed through the perforations 10, after which the nuts 11 of the terminal rods may be applied to hold the end wall 9 in position. Assuming the cells to be within the compartments and properly connected, a seal 12 of molten pitch, or the like, is poured into the open side of the box A, filling the box above the cells and running into the spaces of the compartments and thus practically embedding the cells within the compartments. It is preferred to have this sealing compound 100

come flush with the free edges of the flanges of the box A.

After the cells have been assembled in the box A and the open side of the box sealed, the assembly is introduced endwise through the open end of the outer box, or casing, C. In Fig. 2, the battery-assembly is shown not fully introduced into the outer casing, and it will be understood that the end wall 9 of the inner box has been removed for purpose of illustration. In practice, if desired, the end wall 9 of the inner box may be discarded after the sealing compound has been introduced and has become hardened.

After the battery-assembly has been introduced within the outer container C, reinforcing strips 13, which may be of wood, are placed above the wall 9, which now constitutes the top wall of the inner pasteboard box A. The closure C' is then applied. This closure preferably comprises a pasteboard strip 14 having pasted to its outer surface a paper covering 14^a provided with marginal flaps 14^b which extend downwardly over the upper margin of the upright container C and pasted, or cemented, thereto.

It will be understood that in Fig. 4, for example, the battery has been laid on its side, so that the top of the battery is toward the left-hand side of the figure. The sealing compound 12, therefore, forms one vertical wall of the inner battery-assembly. The terminals 6, 7 and 8 extend through perforations 15 with which the closure of the outer container is provided. Washers 16 are applied outside of the closure, and it will be understood that conductors may be connected by clamping them between the washers 16 and the nuts 11.

The terminal rod 6 has its base end soldered to a brass-strip 17 which extends along the zinc cup 3 of the cell, but which is separated from the zinc cup by a pasteboard strip 18. One end portion of the strip 17 is bent over the end of the cell, as indicated at 17^a and soldered to the brass cap 4^a of the carbon pole 4. The brass strip 17 preferably is secured to the body of the cell by means of tapes 19 before the cell is introduced into the assembly.

The terminals 7 and 8 are connected with the zinc cups of the respective cells by soldering their base portions to the cups, as indicated at 20 in Fig. 5. It will be noted that the strips 17 which connects the terminal 6 with the carbon pole at one end of the cell-series is embedded in the pitch compound 12. The connections 5 between the cells are likewise embedded in the sealing compound.

It is preferred to equip the terminals with nuts 21 which serve as a bearing for the lower side of the pasteboard box 14 of the closure.

In the modification shown in Fig. 6, the construction is similar to the construction

already described, and corresponding parts are correspondingly lettered. In this modification, however, the sealing compound, designated 12^a, does not come quite flush with the free edges of the flanges of the inner box A. To fill out the box, a pasteboard plate 22 is introduced. Also, the closure, designated C', is of modified construction. In this case, the closure comprises an outer pasteboard piece 23 which bears upon the upper edge of the casing C; and a thick piece of pasteboard 23^a which is cemented to the inner side of the pasteboard piece 23, as indicated at 23^b. The heavy reinforcing pasteboard piece 23^a fits snugly within the upper end of the casing C and rests upon the fillets 13^a, if the latter be used. Thus, it will be understood that in this construction the closure C' is held in position by means of the terminals with which the battery is provided. If desired, a suitable paste, or glue, may be introduced about the edges of the closure so that after the closure is applied, it will be bonded to the upper margin of the box, or casing, C.

It has been found, in practice, that the improved construction is admirably adapted for use in situations where a radio battery is to be placed in upright position. Frequently, the space within cabinets provided for radio purposes is limited. Hence, there is a large demand for batteries which, while the cells may be horizontally disposed, have their terminals extending through the top wall of the casing.

It will be noted, with reference to the improved structure, that each cell is securely housed and sealed within a compartment, so that the battery is not liable to be injured by oozing of electrolyte. The use of a sealing compound in the upper end of the other container is unnecessary. By omitting the top seal, the battery is made lighter and cheaper.

It may be explained that it is unnecessary to sever the end 9 from the inner box A shown in Fig. 1. Instead of doing so, the cells which are equipped with laterally projecting terminals may be introduced into the box before the cellular structure A' is introduced, thus enabling the terminals to be entered through the perforations 10 by a parallel movement of the cells. After this, the egg-crate structure may be introduced into the box and the assembly proceeded with as above described. In this case, the end wall 9 of the box will remain integral with the body of the box A.

Referring again to the end wall 9 of the inner container shown in Figs. 1 and 2, it may be stated that instead of applying nuts to hold the end wall in position, the box A may be held within clamps upon a suitable table. In practice, a number of inner assemblies may be arranged in series on a table and

held by suitable clamps while the sealing compound is poured in.

Also, it is unnecessary to use the end wall 9 of the inner box in the final assembly of 5 the battery. Likewise, the fillets 13 may be omitted, if desired. For example, in Fig. 6, the length of the outer casing C may be shortened, and the pasteboard piece 23^a may contact, or substantially contact, with the adjacent end of the inner assembly shown in Fig. 2, both the end wall 9 and the fillet-strips 13^a being omitted. In such case, or in any case, if desired, a layer of molten asphalt 24 may be poured into the bottom of the casing 10 C before the inner battery assembly is slid into the casing. Thus, it will be understood by reference to Fig. 2 that when the box A and its contents are forced into the container C, the lower end of the box A will become 15 embedded in the melted asphalt and so will be firmly joined to the bottom wall of the casing C. The asphalt layer 24 may be of sufficient depth so that the other end of the inner assembly will substantially contact 20 with the closure C' when it is applied.

The foregoing detailed description has been given for clearness of understanding only, and no unnecessary limitations should be understood therefrom, but the appended 25 claims should be construed as broadly as permissible, in view of the prior art.

What we regard as new, and desire to secure by Letters Patent, is:

1. The method of constructing a dry-battery which comprises: coating the inner side of the bottom of a pasteboard box with a sticky compound, introducing a pasteboard egg-crate structure into said box and forcing the lower edges of the pasteboard into said 35 coating, introducing dry-cells into the compartments thus formed with the carbon poles of said cells presented to the open side of said box, connecting said dry-cells in series, cells of a marginal row being provided with terminals which project laterally from the sides of the cells, introducing a sealing compound into the open side of said box to form a common seal for said cells in which the cell connections are embedded, slipping the assembled battery described endwise into an open-ended casing, and applying a closure to said casing which is provided with perforations through which said terminals extend.

2. The method of constructing a dry-battery which comprises: providing a pasteboard box having an open side with compartments, introducing cells into said compartments, some of the cells of a marginal row having terminals projecting laterally from the sides 50 of the cells, connecting the cells in series, introducing a sealing compound into the open side of the box to form a common seal covering and embedding said cells and connections, introducing the assembled battery thus described endwise into an open-ended outer cas-

ing, applying a closure to said casing which is provided with perforations through which said terminals extend, and applying nuts to said terminals outside said closure.
